UNITED STATES PATENT OFFICE.

HARRY J. CALDWELL AND JAMES R. BARR, OF EARLPARK, INDIANA.

PROCESS OF TREATING GRAIN.

SPECIFICATION forming part of Letters Patent No. 761,445, dated May 31, 1904.

Application filed January 25, 1904. Serial No. 190,601. (No specimens.)

To all whom it may concern:

Be it known that we, HARRY J. CALDWELL and JAMES R. BARR, citizens of the United States, residing at Earlpark, in the county of Benton and State of Indiana, have invented certain new and useful Improvements in Processes of Treating Grains, of which the following is a specification.

Our invention relates to improvements upon the processes heretofore in vogue in the treatment of discolored, musty, smutty, and otherwise damaged or unmarketable grains, which may be improved by subjection to sulfurous or like fumes.

15. The object of our invention is to more effectively and economically treat grains with a minimum of waste of materials used, with no danger from fire, with an absolute avoidance of all danger of overheating the grain, 20 and so as to obtain the desired results without injuring the quality of the grain either as to flavor, odor, or otherwise. These and such other objects as may hereinafter appear are attained by the practice of our improved process, which may be operated with the operatives shown in the accompanying drawings, 25 in which—

Figure 1 is a vertical sectional view of an apparatus suitable for practicing our improved process, and Fig. 2 is a plan view of the same.

Like letters of reference indicate the same parts in both figures of the drawings.

Referring by letter to the accompanying drawings, A indicates a stack of a suitable and familiar type, although it is not essential to the practice of our process that a stack of this form be used or that the grain be treated while moving. This stack consists, essentially, 35 of a vertical shaft, which may, if desired, be provided with deflecting-shelves B and with any suitable means (not shown) for directing grain into the upper part of the stack and for permitting the escape or vent of the fumes or 40 vapor from the upper part of the otherwise closed stack.

C is the outlet-chute, and D is a suitable slide for controlling the escape of grain from the stack. It should be understood, however, 45 that our process can be used in the treatment

of grains whether falling through a stack or confined in any other suitable receptacle.

E serves merely to indicate roughly a familiar form of furnace for generating sulfur fumes. Although we prefer to furnish the 55 sulfur fumes by generating them in this manner, our process is not limited thereto.

F indicates a suitable conduit with damper or valve f, leading from the sulfur-furnace to the induction pipe or port of a fan G. The 60 conduit F is provided with one or more ports H I, through which atmospheric air can be admitted in controllable quantities to be governed by the operation of the dampers J. Leading from the fan G is a conduit or education-pipe K, which terminates in a submerged nozzle k within the tank L.

Water is supplied to the tank in any suitable manner—as, for instance, by means of an elevated reservoir M, from which a pipe m 70 leads to the tank L, the flow of water from the pipe M into the tank L being controlled in a familiar manner by a float-valve N. The sulfur fumes or a mixture of fumes and air, as the case may be, forced by the fan G 75 through the pipe K and through the nozzle k rise through the water in the tank L, thereby impregnating the water in said tank with the sulfur-fumes, forming a diluted sulfurous acid or a solution of sulfurous acid. The 80 fumes which are not absorbed by the water in the tank L will rise and are forced through the pipe O, which leads to a suitable port communicating with the interior of the stack A, thus forming a forced circulation for the 85 fumes through the stack A upward to the vent for their escape. It will thus be seen that with the apparatus in operation a portion of the fumes generated in the furnace is absorbed by the water in the tank L, while 90 the balance of the fumes are cooled and, if desired, diluted by the admission of atmospheric air through the ports H and I and are conducted into the stack A. It will thus be seen that the fumes conducted into the stack A 95 have been so cooled that all danger of fire and all danger of heating the grain are eliminated, and all possibility of fire being transmitted from the furnace or conduit pipe to the grain or grain-casing has also been eliminated. It 100

is well understood in this art that in order to obtain the most effective results the grain must be superficially moistened before the sulfur fumes or the sulfur applied to the surface of the grain will satisfactorily act thereon for the purpose of restoring the color and natural condition of the grain.

It is commonly stated that the grain must be first moistened and then subjected to the action of the sulfur, whether in the form of fumes or otherwise; but in actual practice it matters little, if any, whether the moistening element is admitted to the treating-chamber at a point above, on a plane with, or below the point at which the sulfur fumes are admitted, for the reason that after the apparatus is fairly in operation the entire interior of the treating-chamber becomes filled with a heavy humid atmosphere carrying a substantially homogeneous mixture of fine spray or vapor and sulfurous fumes.

In the drawings we have shown a convenient arrangement in which the moistening-jet is admitted to the treating-stack along- side of the port for the admission of the sulfurous fumes.

In order to most efficiently utilize the sulfur and also to most effectively and rapidly treat the grain, we conduct live steam from the boiler through a pipe P, which is controlled by a valve Q, into a nozzle R, which discharges into the interior of the stack A, and with water from the tank L (or other source) admitted at the same point the steam serves to reduce the water to a spray as it is thrown onto the grain.

In order to supply sufficient moisture, we may provide any suitable means—as, for instance, a force-pump S—for withdrawing from the tank L the water which is more or less permeated with the sulfurous fumes and for conducting this sulfur-impregnated water to a point adjacent to the steam-jet, escaping from the pipe P. The steam-jet creates a forced draft through the treating-chamber A and injects and sprays into the treating-chamber A the water supplied through the pipe T from the tank L, the water at the same time serving to condense and cool the steam, so that the moisture which is superficially applied to the grain to be treated is itself in the form of a weak solution of sulfurous acid which of itself has bleaching qualities. The steam is cooled as it enters the treating-chamber, and at the same time the steam serves to create a forced draft and to carry the supply of fumes and moisture upward through the chamber and out through any suitable vent provided therefor. Meanwhile the float-valve N serves to maintain the desired level of water within the tank L. While this is a preferred way of practicing our process nevertheless it is not essential that the water from the tank L be used. For example, we may rely upon the normal condensation of the steam-jet to

provide moisture, or we may admit air through the pipe U, which communicates with the nozzle R and is controlled by the valve V, or we may apply moisture in any other manner. In that event we still attain all of the advantages which arise from cooling the sulfurous fumes by passing them through a comparatively cool fluid. On the other hand, the separate steam-jet is non-essential, for by continuously heating the water in the tank L—as, for instance, by passing the heated fumes therethrough—vapor will be generated and rising with the fumes through the pipe O will enter the stack and furnish sufficient moisture for the purposes of our process. Such vapor can never greatly exceed 212° Fahrenheit in temperature and will rapidly condense as it enters the stack A.

As previously stated, although we have shown in the drawings one suitable form of apparatus with which our improved practice may be operated, it should be noted that the grain may be confined in any suitable manner so as to be subjected to the action of moisture and the sulfurous fumes, any suitable means may be utilized for spraying the grain, and any suitable means may be utilized for preparing or treating water before it is applied as a moistening element to the surface of the grain.

With the particular apparatus shown it will be noted, however, that a suitable metallic fan may be utilized for driving the fumes or fumes and air mixed. The fumes are quickly and effectively cooled, the bleaching action of the sulfurous element begins as soon as the moisture is applied to the grain, and the actual fumes applied to the grain may be so diluted that there will be little or no waste of the treating materials. Again, sulfurous fumes, whether pure or mixed with air, are hot or warm, as the case may be, the temperature being determined by the amount of air mixed with the fumes. Now these fumes, clear or mixed with air, when forced through a fluid element will mechanically take up some of the fluid element and carry it to the grain to be treated.

If the fluid element is heated sufficiently by the fumes passing through it or heated sufficiently by any other means, such fluid element will give off sufficient steam or vapor to moisten the grain to be treated sufficiently, so that no other or additional moisture will be needed.

In this method the fluid element will absorb the fumes or sulfurous gas forced through it until the point is reached beyond which it cannot absorb any more, at which point the fumes will pass through the fluid element without losing any of their strength or volume. Still the fluid element will be just as complete a protection against fire being carried from the furnace or conduit pipe to the stack A or the building or the grain to be treated (a possibility claimed by some insurance people in the old style of construction, where the fumes were not passed through a fluid) as though we were

using the sulfur-impregnated fluid for moisture and constantly changing such fluid element.

We claim—

- 5 1. The process of treating grain, which comprises subjecting the grain to the action of a mixture of fumes which have been passed through a fluid element, and vapor which has been generated from said fluid element.
- 10 2. The process of treating grain which comprises spraying the grain with water which has been previously treated with sulfurous fumes.
- 15 3. The process of treating grain, which comprises spraying the grain with water which has been treated with sulfurous fumes, and also subjecting the grain directly to the action of sulfurous fumes.
- 20 4. The process of treating grain, which comprises injecting a spray of moisture impregnated with sulfurous fumes into an inclosure containing the grain to be treated.
- 25 5. The process of treating grain, which comprises injecting sulfurous fumes against grain in an inclosure, said grain having been superficially treated with moisture impregnated with sulfurous fumes.
- 30 6. The process of treating grain, which comprises generating sulfurous fumes, conducting said sulfurous fumes through water, spraying the grain with water through which the sulfurous fumes have passed, and treating the grain to the fumes which have passed through the water.
- 35 7. The process of treating grain, which comprises conducting sulfurous fumes through a fluid element, spraying the grain with said fluid element, and treating the grain with the sulfurous fumes which have passed through the fluid element.
- 40 8. The process of treating grain, which comprises generating sulfurous fumes, forcing the same through a comparatively cool fluid element, spraying the grain with a spray com-

posed in part of the fluid element through which the sulfurous fumes have passed, and also subjecting the grain to the action of said sulfurous fumes which have passed through the cooling fluid element.

9. The process of treating grain, which consists in continuously passing the grain through a closed vertical stack, generating sulfurous fumes, forcing said sulfurous fumes through a comparatively cool body of water, conducting said fumes which have passed through the water into said stack, and spraying the grain with a spray composed in part of the water through which the sulfurous fumes have passed.

10. The process of treating grain, which comprises generating sulfurous fumes, diluting the same with controllable quantities of air, forcing the mixture of fumes and air through a body of comparatively cool fluid element and then into an inclosure containing the grain to be treated, and injecting the fluid element, through which the fumes have passed, into said inclosure, so as to superficially moisten the grain.

11. The process of treating grain, which consists in causing the grain to continuously pass through a closed vertical stack, generating sulfurous fumes, forcing the sulfurous fumes through a comparatively cool body of water and then into the treating-stack, injecting a jet of steam into said treating-stack, and conducting the water through which the fumes have passed to a point adjacent to the jet of steam, so that the grain within the stack shall be subjected to a moistening-spray composed in part of the water through which the fumes have passed.
